UNITED STATES PATENT OFFICE.

WILLIAM R. CUNNINGHAM, OF BUCYRUS, OHIO, ASSIGNOR TO THE AMERICAN CLAY MACHINERY COMPANY, OF BUCYRUS, OHIO, A CORPORATION.

CUTTING-WIRE.

No. 852,107.

Specification of Letters Patent.

Patented April 30, 1907.

Application filed March 4, 1907. Serial No. 360,551.

To all whom it may concern:

Be it known that I, WILLIAM R. CUNNINGHAM, a citizen of the United States, residing at Bucyrus, in the county of Crawford and 5 State of Ohio, have invented new and useful Improvements in Cutting-Wires, of which the following is a specification.

My invention relates generally to new and useful improvements in cutting devices for 10 brick and tile cutting machines or to any machine whereby a slab, column or mass of formed clay or other plastic or semi-plastic material is cut into forms representative of bricks, tiles or other products.

15 The present invention relates more specifically to the cutting table portion of the type of machines above mentioned, and it is applicable to the usual reciprocating and the oscillating form of frame or carriage or in 20 fact to any frame or carriage or other device wherein cutting wires are strung under tension and which sever the bar or column of clay or other material in suitable lengths as the wires are passed therethrough.

25 The object of the present invention is to so improve the attaching ends of the aforesaid cutting wires, that the wires are more readily placed in position to lessen the liability of the wire breaking; and to shorten the time 30 required to remove a broken or damaged wire and substituting therefor a new wire.

With these primary objects in view, my invention consists, essentially, in supplying the attaching end of the wire with a fixed 35 sphere or enlargement through which the wire is passed and its protruding end substantially returned upon itself and thence carried across the body portion to form a small loop or knot, which prevents the wire being pulled 40 out of the sphere or enlargement or the latter being stripped from the wire under the tension or strain to which the wire is subjected.

In the accompanying drawing forming 45 part of this specification, the figure represents a fragment of one form of wire holder for the cutting table of a brick or tile cutting machine, showing my improved cutting wire and the manner of attaching it to said holder.

50 In this art, as far as I am aware, the method usually adopted for securing wires in the holder, is to twist the end of the wire to form a loop, said loop being thus adapted to hook over a hook or pin on the holder.

Experience has shown that the twisting of 55 the wire, because of crystallization or other causes, greatly weakens the wire at the point of twisting and causes the wire to break; it also often occurs that during the twisting operation the wire—which is usually made of 60 steel—is fractured.

In carrying out my invention I use in connection with the wire an enlargement which may be of spherical or other design but which, preferably, is in the form of a ball A, 65 which term I will hereinafter use in referring to this part although I do not limit myself to a round enlargement since one of other forms may be used with success and without departing from the scope of my true invention. 70

The ball A, I provide with a hole B which may be drilled or otherwise made, and through this hole the end of the cutting wire C is passed for a suitable distance. The 75 protruding free end of the wire I now fold back to form a small loop C', the free end of the wire being carried across the wire substantially at the point where the wire emerges from the hole in the ball A; thereby forming 80 substantially a knot which prevents the wire being pulled out of the ball or, in other words, the ball stripped from the wire, by any pressure or strain tending to move one of the parts oppositely and relative to the other. 85

If desired and to obtain additional security from the ball being displaced relative to the wire, I may solder the ball in place.

The small loop C' formed at the end of the wire is not to be confounded with the loop 90 usually provided at the end of a cutting wire exterior to a twisted portion and which hooks over a pin or hook on the wire holder since the loop on my wire is merely intended to hold the ball in place, the ball itself being 95 the attaching member and being designed to rest in contact with the forks of a suitable bifurcated support of substantially the form of a claw-hammer, the wire itself being passed into the space between said forks, as 100 shown.

By reason of the construction described, I am enabled to shorten the time required to place a wire in position in its holder, when a wire should break, and by constructing the 105 wire with the ball, I lessen the liability of the wire breaking from being fractured in twisting.

Having thus described my invention what I claim as new and desire to secure by Letters Patent is:—

1. A cutting wire having an enlargement 5 through which the wire passes, the end of said wire being extended beyond the enlargement and being looped across itself exterior to the enlargement to form a retaining means for the enlargement.
- 10 2. A cutting wire and a ball at the attaching end thereof, said wire being passed through the ball and having its projecting end looped backwardly transversely across the wire at substantially the junction of the 15 wire with the outer surface of the ball, and retaining the ball in place on the wire.

3. The combination with a claw-shaped hanger, of a cutting wire having a ball member seating against the claws of the hanger with the wire entering the space between the claws, said wire having its outer end projected beyond the ball and thence looped back substantially upon and transversely across itself, and exterior to the ball member and in contact with said ball member. 25

In testimony whereof I have hereunto set my hand in presence of two subscribing witnesses.

WILLIAM R. CUNNINGHAM.
